UNITED STATES PATENT OFFICE.

JAMES F. OREBAUGH AND CHARLES W. CONNETT, OF MADISON, INDIANA; SAID CONNETT
ASSIGNOR TO SAID OREBAUGH.

GASOLENE TURBINE-MOTOR.

No. 884,846.

Specification of Letters Patent.

Patented April 14, 1908.

Application filed May 25, 1907. Serial No. 375,675.

To all whom it may concern:

Be it known that we, JAMES F. OREBAUGH and CHARLES W. CONNETT, citizens of the United States, residing at Madison, in the county of Jefferson and State of Indiana, have invented new and useful Improvements in Gasolene Turbine-Motors, of which the following is a specification.

This invention relates to gasolene turbine 10 motors, and one of the principal objects of the same is to provide a motor of the turbine type to be actuated by successive charges of hydro-carbon gas.

Another object of the invention is to overcome some of the defects of the crank-shaft 15 type of motors by increasing the leverage and overcoming the dead center.

Another object of the invention is to provide means for utilizing every atom of force 20 in the ignited and expanding gas with a view to saving fuel and to making the explosion chambers self-cleaning, so that the entire force of the discharge will be utilized, and the burned gases removed from the explosion 25 chambers at each firing.

Another object is to simplify the construction and to reduce the weight of motors of the character referred to without decreasing the efficiency of the same.

These and other objects may be attained 30 by means of the construction illustrated in the accompanying drawings, in which:

Figure 1 is a longitudinal vertical section of a motor made in accordance with our invention. Fig. 2 is a front to rear longitudinal section of the same. Fig. 3 is a vertical section on the line 3—3, Fig. 2, looking in the direction indicated by the arrows. Fig. 4 is a plan view of one of the rotors. Fig. 5 40 is a sectional view of two of the rotors connected to a broken away portion of the shaft. Fig. 6 is a sectional view of a portion of a plurality of rotors of modified form. Fig. 7 is a detail side elevation of one of the rotors 45 shown in Fig. 6. Fig. 8 is a detail sectional view of the same.

Referring to the drawings for a more specific description of our invention, the numeral 1 designates a casing having at one end an 50 extended reduced portion 2 provided with an exhaust port 3. The opposite end of the casing is provided with an opening 4, and covering said opening upon the inside of the casing is a wire gauze screen 5. A central shaft 6 extends through the casing and is journaled

in bearings 7 provided with screw caps 8, said bearings and cap having raceways provided therein for the balls 9, thus providing ball bearings at opposite ends of the casing. A fan 10 is secured to the shaft 6 adjacent to 60 the screen 5 for drawing air through the opening 4 and projecting it through the interior of the casing to keep the parts cool. A fan 11 is secured to the shaft 6 in the exhaust chamber for driving the exhaust out through the 65 port 3. A partition 12 is fixed in the casing, said partition having an aperture through which the shaft 6 extends, and secured to this partition is a series of explosion chambers 13, three of said chambers being shown 70 in the drawing, but it will be understood that any suitable number may be utilized. The explosion chambers 13 each consists of a tube open at its opposite end and provided with a series of cooling flanges 14 upon the outer 75 sides thereof, the bore of the tube being enlarged at one end. An inlet pipe for the fuel extends through one end of the casing, said pipe 15 having branches 16 fitted in threaded inlet ports 17 disposed centrally to the explosion 80 chambers. Fitted in the smaller ends of the explosion chambers are the plungers 18 for compressing the gas, said plungers being provided with suitable packing rings 19. The plungers 18 at their outer ends are provided 85 with a cross pin 20 and engaging said cross pin is a lever 21 having a slotted end 22, said levers each being pivotally connected to a boss 23 extending outward from the partition 12, a bolt 24 extending through the lever 90 21 and into the boss 23, suitable washers 25 being disposed upon opposite sides of said lever. Each of the levers 21 is provided with an offset 26, and on the free end of the lever is a roller 27 which engages a cam groove 28 95 in a cam 29 keyed to the shaft 6. In the enlarged end of the explosion chamber is fitted a spring seated piston head 30, the end of which is beveled, as at 31, to fit the beveled seat in the explosion chamber. The stem 31 100 of the piston 30 extends through a cap 32 fitted to the outer end of the explosion chamber, and a spring 33 encircles the stem and bears at one end against the head 30 and at the opposite end against the cap 32. The 105 stem 31 extends into a buffer 34 bolted at 35 to the partition 12, and a bolt 36 extends through the buffer 34, and is connected to the flanges 14, said bolt 36 being provided with a nut 37 which bears against the buffer 110

34 and provides means for adjusting the buffer against the tension of the spring 33 to regulate the resistance of the head 30 to the explosive force of the charge.

5 The sparking plugs 38 which may be of the usual or any suitable type communicate with the explosion chambers, as shown in Fig. 3, said plugs extending through openings 39 in the casing 1. An air inlet valve 40 seated by 10 a spring 41 is provided with a roller 42 connected to the stem of the valve, said roller engaging a groove 43 in the periphery of the cam 29 to admit air to the explosion chambers to be mixed with the gas prior to the 15 sparking operation.

The rotors each consists of a hub 44 keyed to the shaft 6, and a series of spokes 45 extending from the hub and provided with an integral rim 46. A series of vanes or buckets 20 47 having concave upper surfaces and convex lower surfaces, are secured to the rim 46 at their inner ends, and their outer ends are secured to an outer ring or annulus 48. Between each pair of the rotors is a stationary 25 flange 49 through which a bolt 50 passes, said bolt extending through spacing sleeves 51 intermediate the flanges 49 and said bolt extending through an aperture in the partition 12 and provided with a nut 52 for securing 30 the flanges rigidly thereto. At the inner ends of the flanges 49 concave buckets 53 are provided, said buckets being set oppositely to the vanes or buckets 47 of the rotors. An inclined inlet opening 54 extends through the 35 wall of the explosion chamber and through the partition 12, said inlet opening communicating with the enlarged portion of the explosion chamber and the opposite end of said inlet opening being disposed at an angle to the concave buckets 47 so that the impact of 40 the charge will give a rotary impulse to the rotor adjacent to the partition 12, while the expansive force of the charge will be utilized by the succession of rotors until the same 45 reaches the exhaust chamber.

As shown in Figs. 6, 7 and 8, the rotors each consists of a hub 55, spokes 56 and an integral rim 57 provided with apertures 58 having inclined walls 59, and secured between 50 each pair of rotors is a fixed abutment wheel 60 having a series of apertures 61, the walls of which are plain, as at 62, said apertures communicating with the inclined apertures 58 in the rotors.

55 The casing 1 may be made in sections and may be secured together by means of the flanges 63 and the bolts 64.

The operation of our invention may be briefly described as follows: The charge of 60 fuel being admitted at the proper time to the explosion chamber and air being admitted by the unseating of valve 40, the plunger 18 is moved forward to compress the charge and when it is ignited its expansive force pushes 65 the piston head 30 outward against the ten-

sion of the spring 33 until said head 30 passes beyond the inlet port 54, the plunger 18 still continuing in its movement to force the last atom of the charge through the port 54 against the concave buckets 47 of the rotor 70 adjacent to the partition 12. The charge is then transmitted from the buckets 47 through the openings in the stationary flanges to the next rotor, and so on until the charge reaches the exhaust chamber and is 75 driven out through the port 3 by the fan 11. To start the motor we may provide a compressed air tank for giving the initial start to the rotors, or in lieu of this arrangement, we may merely utilize a crank for starting. 80

From the foregoing it will be obvious that a motor made in accordance with our invention is simple in construction, is compact, is light in weight, is accumulative in action, utilizes all the explosive gases, and is kept 85 cool by the fans, while the explosion chambers are kept clean owing to the action of the plungers 18 and the spring pistons 30.

Having thus described the invention, what we claim is:

1. In a motor, the combination of a casing, a partition secured to said casing, a series of explosion chambers fixed to said casing, compressing plungers mounted to reciprocate in the explosion chambers, a spring seated piston head mounted in the explosion chambers, means for moving the plungers inward to compress the charge, a shaft mounted in the casing, and a series of bucketed rotors keyed to the shaft. 90

2. In a motor, the combination of a casing, a partition secured in the casing, a series of explosion chambers secured to the partition, a plunger adapted to reciprocate in one end of said explosion chamber, a lever connected to each of said plungers, a cam for moving said levers and plungers, a spring seated piston mounted in the opposite end of each of said explosion chambers, an adjustable buffer for said pistons, means for igniting the charge, a shaft extending centrally through the casing, a series of bucketed rotors keyed to the shaft, and intermediate stationary flanges between each pair of rotors. 105

3. In a motor, the combination of a casing, a shaft mounted in the casing, a fan carried by the shaft and disposed at opposite ends of the casing, a partition in the casing, explosion chambers secured to the partition, a plunger mounted to reciprocate in each 115 chamber for compressing the charge, means for reciprocating the plungers, a spring seated piston in the opposite end of the chambers, means for igniting the charge, means for admitting air to the chambers, a series of rotors 120 keyed to the shaft, and means for admitting the exploded charge to the rotors. 125

4. In a machine of the character described, the combination of a casing, explosion chambers in said casing, a plunger mounted to re- 130

- ciprocate in one end of each of said explosion chambers, means for reciprocating said plungers, a spring seated piston mounted in the opposite ends of said explosion chambers, an 5 adjustable buffer for regulating the tension of the springs, a shaft journaled in the casing, a series of bucketed rotors fixed to said shaft, igniting devices, and means for admitting air to said explosion chambers.
- 10 5. In a motor, the combination of a casing, a partition secured in the casing, a series of explosion chambers connected to the partition, a reciprocating plunger for each explosion chamber, a spring seated piston for each

explosion chamber, igniting devices, an air 15 inlet valve for each of said explosion chambers, a roller connected to the stem of said valve, a cam provided with a groove for said roller, a shaft mounted in the casing, a series of bucketed rotors connected to the shaft, 20 and fans connected to said shaft.

In testimony whereof, we affix our signatures in presence of two witnesses.

JAMES F. OREBAUGH.
CHARLES W. CONNETT.
